UNITED STATES PATENT OFFICE.

HIRAM L. TRUE, OF McCONNELLSVILLE, OHIO.

DESIGN FOR AN INHALER.

SPECIFICATION forming part of Design No. 33,125, dated August 28, 1900.

Application filed July 14, 1900. Serial No. 23,678. Term of patent 14 years.

To all whom it may concern:

Be it known that I, HIRAM L. TRUE, a citizen of the United States, and a resident of McConnellsburg, in the county of Morgan and State of Ohio, have invented and produced a new and original Design for an Inhaler; and I declare the following to be a full, clear, and exact description of the same, such as will enable others skilled in the art to which it appertains to make and use the invention, reference being had to the accompanying drawings, and to letters of reference marked thereon, which form a part of this specification.

Figure 1 is a side view of the inhaler. Fig. 2 is an end view of the same. Fig. 3 is a view from the opposite end of the inhaler.

The invention relates to a new and original design for inhalers; and it consists in the novel form and configuration of the inhaler, as hereinafter shown and described.

As shown in the drawings, the leading or material feature of my design consists of a

hollow globular enlargement A, having on one side a small tubular extension B, terminating in an open beaded end or mouth C. 25 On the opposite side of the globular portion A from the small tubular extension is a tubular extension D of larger diameter, terminating in an open end or mouth e, having a rounded rim. These tubular extensions B and 30 D are in axial line with each other, and the larger tubular extension is about double the diameter of the smaller tubular extension.

Having described my invention, what I claim as new, and desire to secure by Letters 35 Patent, is—

The design for an inhaler, substantially as specified.

In testimony whereof I affix my signature in presence of two witnesses.

HIRAM L. TRUE.

Witnesses:

EDGAR SHARP,
O. T. MASTERSON.
